UNITED STATES PATENT OFFICE.

ALEXANDER LOUGHIN AND ELLIS L. FOX, OF PORT KENNEDY,
PENNSYLVANIA.

CHEST.

SPECIFICATION forming part of Letters Patent No. 595,955, dated December 21, 1897.

Application filed March 23, 1897. Serial No. 628,893. (No model.)

To all whom it may concern:

Be it known that we, ALEXANDER LOUGHIN and ELLIS L. FOX, citizens of the United States, residing at Port Kennedy, in the 5 county of Montgomery and State of Pennsylvania, have invented a new and useful Chest, of which the following is a specification.

Our invention relates to chests, particularly of that class adapted for containing perishable articles or those which are exposed to the 10 attacks of moths, mice, and other vermin; and the object in view is to provide a chest which is not only adapted to prevent the entrance of vermin, but is waterproof and fire- 15 proof.

Further objects and advantages of this invention will appear in the following description, and the novel features thereof will be particularly pointed out in the appended 20 claims.

In the drawings, Figure 1 is a perspective view of the chest closed. Fig. 2 is a similar view with the lid raised. Fig. 3 is a longitudinal section. Fig. 4 is a transverse section. Fig. 5 is a perspective view of a portion of the skeleton or frame of the body of 25 the chest.

Similar numerals of reference indicate corresponding parts in all the figures of the drawings.

The skeleton or frame comprising the body portion of the chest includes a bottom or base board 1, from the extremities of which rise end boards 2, which form the body portions 30 of the end walls of the chest, and these end boards are connected at their front and rear edges, respectively, by lock and hinge rails or bars 3 and 4, terminally let into the end boards and secured by any suitable fastening 35 devices, such as nails. (Shown in Fig. 5.) Before the lock and hinge rails are let into the seats provided therefor in the end boards a thin veneer strip 3^a 4^a, of cedar, is arranged in contact with each of the rails and extends 40 terminally into the rail-seats, whereby when the rails are secured in place said veneer strips are similarly fastened. Also arranged upon the upper surface of the bottom or floor of the chest and equal in length with the 45 interval between the inner surfaces of the end boards is a bottom veneer strip 1^a, which is

terminally secured in place by means of end veneer strips 2^a, arranged in contact with the inner surfaces of the end boards 2. The lower edges of said end veneers bear upon the upper surface of the bottom veneer, while the upper portions of the side edges of the end veneers are cut away to form shoulders 2^b, which engage under the lock and hinge rails. Additional fastening devices for the end veneers are provided by the eyebolts 5, to which the handle-grips 6 are attached, said handle-grips being provided with terminal trunnions mounted in the eyes of the bolts.

The front and rear walls of the chest are 65 completed below the lock and hinge rails by side veneers 7, which are secured to the front and rear edges, respectively, of the end boards 2, the lock and hinge rails extending outwardly beyond the contiguous surfaces of said 70 edges of the end walls to overlap the upper edges of the side veneers.

Covering the exterior surfaces of the bottom, side, and end walls, as above described, is a metallic sheath 8, of galvanized iron, copper, or any other suitable metal or fireproof material, the angles being strengthened by cross-sectionally-angular corner-braces 9, and this sheath is applied in such a way as to have sealed joints, as by cementing the same at 80 the joints, and the upper edge of the sheath is folded inwardly over the side and end walls and is covered by a fireproof packing-strip 10, of asbestos or its equivalent. The inner edge of this packing-strip is flush with the 85 inner surfaces of the contiguous angles, which are arranged, respectively, in contact with the end boards and the lock and hinge rails. The outer edge of said packing-strip is flush with the exterior surface of the sheath.

The top or cover of the chest comprises a body portion 11, of pine or other wood of low market value, (similar to that which is preferably used for the bottom, end walls, and connecting-rails of the body of the chest,) and 95 secured to the inner or under surface of this body portion is a veneer 12, of cedar. Asbestos or equivalent fireproof packing-strips 13 are let into the inner or under surface of said top veneer for contact with the strip which is 100 arranged upon the upper edges of the side and end walls of the chest. Also surrounding

the top or cover at the three edges not provided with hinges is a break-joint strip 14, which depends below the lower or inner surface of the veneer and packing-strip 13 and 5 also extends below the upper surface of the packing-strip 10 to bear against the upper edge of a cap-strip 15, secured to the side and end walls of the chest and projecting beyond the exterior faces thereof. The break-joint 10 and cap strips are preferably of cedar, and it is obvious that as the joint therebetween is not in the plane of the joint between the packing-strips of the top and body portion of the chest said packing-strips are protected and 15 remain in condition for efficiently performing their function.

The chest is provided with any suitable or preferred form of lock and hinges, which, however, form no part of the present invention 20, and the corners of the top or cover are provided with protecting or bracing plates 16.

Inasmuch as the veneer, of which the entire interior or lining of the chest is constructed, consists of cedar, it is obvious that 25 moths will be effectually excluded, while the metallic sheath, of which the top or cover is provided with a part, as shown at 17, protects the chest and its contents from such vermin as mice and rats and also serves to preserve 30 the chest when exposed to fire. Furthermore, the packing-strips arranged in the joint between the top or cover and the body portion of the chest exclude moisture, which, obviously, cannot enter at any other point on 35 account of the sealing of the joints between the portions of the sheath, and by making said strips of the material named fire and smoke are prevented from gaining access to the interior at said joints.

40 Various changes in the form, proportion, and the minor details of construction may be resorted to without departing from the spirit or sacrificing any of the advantages of this invention.

45 Having described our invention, what we claim is—

1. A chest having a skeleton frame comprising a bottom, end boards, and parallel lock and hinge rails connecting the end boards and 50 terminally let into seats therein, veneer strips arranged in contact with the inner surfaces of the lock and hinge rails and extended terminally into the seats for said rails, side veneers extending from said rails to the bottom 55 a bottom veneer equal in length to the interval between the inner surfaces of the end

boards, end veneers arranged in contact with the inner surfaces of the end boards and bearing at their lower edges upon the upper surface of the bottom veneer to secure the 60 latter in place and an exterior sheath overlapping the edges of the end and side walls, substantially as specified.

2. A chest having a skeleton comprising a bottom, end walls, and connecting lock and 65 hinge rails, bottom and end veneers arranged in contact with the inner surfaces of the bottom and end boards, side veneers arranged below the planes, respectively, of the lock and hinge rails and flush at their outer surfaces therewith, a metallic sheath inclosing the bottom, side and end walls, and overlapping the same at its upper edges, a top or cover having a metallic covering corresponding with said sheath, and packing interposed between the contiguous edges of the chest and 70 said top or cover, substantially as specified. 75

3. The herein-described chest having a skeleton frame comprising a bottom, end boards, and lock and hinge rails, cedar veneers covering the inner surfaces of the parts of said frame, side veneers extending from the rails to the plane of the bottom, a metallic sheath secured exteriorly to the frame and having sealed joints and corner-protecting braces, a 80 top or cover having an interior cedar veneer lining and an exterior sheath-plate, an asbestos packing-strip covering the upper edges of the side and end walls of the chest, a similar packing-strip countersunk into the inner surface of the top veneer, and break-joint and cap strips respectively secured exteriorly to the top or cover and the side and end walls of the chest, and arranged at their contiguous 85 edges in contact, in a plane below that of the meeting surfaces of said packing-strips, substantially as specified. 90

4. A chest having a skeleton frame, a veneer, lining the inner surfaces of the frame members and filling the spaces therebetween 100 to complete the walls of the chest, and an exterior sheath of fireproof sheet metal completely covering the chest, substantially as specified.

In testimony that we claim the foregoing as 105 our own we have hereto affixed our signatures in the presence of two witnesses.

ALEXANDER LOUGHIN.
ELLIS L. FOX.
